UNITED STATES PATENT OFFICE.

HANS KUPELWIESER, OF ST. POLTEN, AUSTRIA.

WALL CONSTRUCTION.

Application filed June 30, 1925, Serial No. 40,555, and in Austria September 2, 1924.

This invention relates to an improved method of producing concrete walls with wood reinforcement for vessels, receptacles, tanks, silos, houses, boats or the like.

The characteristic feature of the present invention consists in that the wood reinforcement, which is covered at one side or both sides with concrete, is formed by a stable structure of supports, provided at both sides with a lath grid. Owing to the employment of a double lath grid as a means of reinforcement, an intimate engagement between the wood and concrete and a mutual penetration of both is attained, which renders possible a satisfactory utilization of the statical peculiarities of the two building materials (wood and concrete). The production of the wood reinforcement in three layers renders possible the use of wooden bars of a small cross-sectional area, whereby the detrimental effect of the "working" of the wood is considerably reduced. Finally the employment of the lath grids greatly facilitates the application of concrete with the aid of the known method of spraying concrete. Owing to the arrangement of the bars of the lath grids in such a manner, that they are displaced with respect to each other, all the clear openings of mesh of the trellis work are covered up in the direction of the concrete jet, so that also in the case of larger openings of mesh the applied concrete strikes against a wooden surface. If desired iron reinforcement may be disposed and embedded in the spaces between the bars of the lath grids.

One mode of carrying out the present invention is illustrated by way of example on the accompanying sheet of drawings in which—

Fig. 1 shows a trellis work in front view.

Fig. 2 illustrates a completed concrete wall in cross-section, and

Fig. 3 is a front view of the trellis work of a wall with the wood reinforcement extending in different directions.

Fig. 4 illustrates a tower partly covered with concrete.

In the illustrated embodiment the wooden framework consists of vertical wooden supports *a*, which are suitably spaced apart and provided at both sides with laths *b* and *c*, displaced with respect to each other and nailed to the said supports. The laths *b* and *c* are arranged with respect to the standards *a* either at a right angle (Fig. 1), or

at any desired angle (Fig. 3). In cross-section the laths are dovetailed or of any other convenient shape (Fig. 2), in order to facilitate the adhesion of the applied concrete. The wooden framework, constructed in the manner above described and forming a separate structure, acts in the manner of ends or wooden bars owing to the crossed disposition of the fibers of the wood in the three layers and in consequence of the nailing. In case it is found necessary to increase the rigidity by means of iron-reinforcements, the latter are disposed either in the spaces between the supports *a* (iron rods *e* in Fig. 1) or horizontal iron rods *h* (Figs. 1 and 2) are arranged on the re-entering surfaces of the laths *b* and *c*. The wooden framework serves for supporting a double-sided concrete-layer *m*, further as an effective support of the concrete-plaster, as a means for facilitating the attachment of any necessary iron insertions, and particularly as a means of reinforcement. Owing to the suitable dimensioning of the distance between the laths all the clear openings of mesh can be covered up, so that in the event of employing the method of spraying concrete, the sprayed concrete cannot be blown right through the structure, whereby however the necessary good engagement between the concrete and wood is satisfied by the peculiar shape of the wooden reinforcement.

Walls constructed according to the present invention are particularly adapted for the construction of thin-walled cylindrical towers (Fig. 4), such as for example silos, water- or oil tanks and so forth. The wooden framework is erected in such a manner, that the supports *a* are arranged in a circle upon a concrete base. For erecting the framework the supports are nailed to a sill, secured to the said base by means of screws let into the concrete, and provisionally secured at two other places to a ring-shaped "gauge", which is clamped at convenient distances to a centrally arranged provisional guide-post. Now the cornice or plate is placed over the upper ends of the supports and the latter are secured thereto. After having put up the door and the vertical supports (which are fixed in the final position by the sill, cornice or plate and the two "gauges") the laths *b* and *c* are nailed to the wooden framework and can be bent in any convenient manner without breaking, owing

to their small thickness. In this stage the wooden framework is ready for the application of the concrete, after having removed the "gauges" and the guide-post.

I claim—

1. In a wall construction of concrete and wood, a wooden structure comprising a series of spaced vertical lath shaped members, a series of lattice-work members applied to the broad faces of the vertical members at an angle thereto, a second series of lattice-work members applied to the opposite faces of the vertical members in such manner that the interstices of the opposing lattice-works are substantially out of alignment with each other, and a concrete casing enclosing the entire wooden structure.
2. In a wall construction of concrete and wood, a wooden structure comprising a series of spaced upright members, a set of spaced parallel members applied thereto on one side to form a lattice-work with interstices, a second set of parallel members applied to the opposite side of the series of upright members to form a similar lattice-work, the interstices of the one lattice-work being substantially closed at their inner ends by the

parallel members of the opposing lattice-work, and a concrete casing upon the sides and within the interstices of the wooden structure.

3. In a wall construction of wood and concrete, a wooden structure comprising a series of closely spaced vertical lath shaped members, a set of parallel members applied to each broad surface of the vertical series at opposite sides thereof and at an angle thereto, and a concrete casing enclosing the entire wooden structure.

4. In a wall construction of wood and concrete, a series of spaced upright members, a set of parallel members applied to one side of the upright members, a second set of parallel members applied to the opposite side of the upright members and in staggered relation to the first set of parallel members, and a mass of concrete enclosing the wooden structure.

5. In the construction defined in claim 4, metal reinforcement bars distributed between the members, and said parallel members being dovetailed in cross section to key the wooden skeleton and concrete together.

HANS KUPELWIESER.
